UNITED STATES PATENT OFFICE.

FREDERICK G. GRANTHAM, OF KANSAS CITY, MISSOURI.

SUBMARINE SCOUTING APPARATUS.

1,324,961.

Specification of Letters Patent. Patented Dec. 16, 1919.

Application filed October 4, 1918. Serial No. 256,895.

To all whom it may concern:

Be it known that I, FREDERICK G. GRANTHAM, a citizen of the United States, residing at Kansas City, in the county of Jackson, State of Missouri, have invented certain new and useful Improvements in Submarine Scouting Apparatus, of which the following is a full and exact specification.

The present invention relates to submarine apparatus, and one of the objects in view is to provide an improved submarine vessel, of what may be termed the one-man type, adapted for submarine scouting purposes. To this end I have devised a vessel of suitable proportions, and with proper ballast construction, and having provision for propelling and guiding the vessel by a single person operating mechanism arranged within the vessel.

It is also sought to provide a construction in which the air supply within the vessel may be effectively controlled and including an air reservoir and pump device adapted to be operated by means of the connections to the propeller drive.

A further object is to provide an apparatus of the character described in which provision is made for releasing the ballast in an emergency, and in which the ballast-carrying section is so arranged as to move, when released, in a manner causing the vessel to assume a position for bringing the head end of the vessel to the water surface.

Another object is to devise an improved scouting type of vessel in which the construction is such as to permit the operator or pilot to have full control of all the mechanism necessary for propelling and guiding the vessel as well as for regulating the air circulation, and at the same time enable him to make all desired observations for scouting purposes.

Further objects will appear in the course of the detail description.

The invention will now be described with reference to the accompanying drawings illustrating one form of construction which has been devised for embodying the proposed improvements, after which the novel features therein will be set forth and defined in the appended claims.

In the drawings—

Figure 1 is a vertical longitudinal sec-

tional view, showing a submarine apparatus constructed in accordance with the present invention;

Fig. 2 is a horizontal longitudinal sectional view, taken on the line 2—2 of Fig. 1;

Fig. 3 is a transverse section, taken on the line 3—3 of Fig. 1;

Fig. 4 is a side elevation, shown on a reduced scale;

Fig. 5 is a fragmentary sectional view, illustrating one of the flexible fin structures;

Fig. 6 is an enlarged detail sectional view, illustrating a part of the driving mechanism; and

Fig. 7 is a perspective diagram showing the pump and connections thereto.

Referring to the said drawings in detail, these illustrate the apparatus as comprising a vessel which may be constructed of any suitable light material (such as aluminum), and providing a main water-tight compartment 10, surrounded at the top and sides by a compressed-air compartment or reservoir 12 (see Fig. 3), within which is located a flexible bag 14 constituting a foul-air compartment provided with a vent 16 communicating with the exterior of the vessel and controlled by a valve 18. The general form of the vessel is illustrated as approximately simulating the outlines of a fish, and at one end is provided with a tail rudder 20 of the shape shown and provided with hinge connections 22 for affording said rudder lateral pivotal movement. The rudder 20 is shifted by means of a bevel gear 24 journaled about the axis of one of said hinges 22 and meshing with a gear 26 on a shaft 28 having a flexible operating connection 30 which is led forward toward the opposite or front end of the vessel into convenient position for operation by the pilot when occupying a reclining position upon a longitudinally extending cushion 32, as illustrated in Fig. 1. The operating connection 30 is provided with a hand wheel 34 journaled in a bracket 35 alongside the cushion 32.

Operating within the rudder 20 is a propeller 36 carried by the outer end of a shaft 38, the inner end of which is supported within a bearing bracket 40 and keyed to a sliding clutch element 42 (see Figs. 2 and 6) adapted to be shifted by a lever 44 mounted

upon said bracket and connected by a rod 46 to a lever 48 which is fulcrumed in a bracket 50 located toward the front of the cushion 32. By this means the pilot may 5 readily shift the clutch element 42 either into or out of engagement with a bevel gear 52 carried by a sleeve 54 (see Fig. 6) mounted on said shaft 38 within the bracket 40. The gear 52 meshes with a gear wheel 10 56 secured to a shaft 58 also journaled in the frame of the bearing bracket 40 and carrying a pair of cranks 60 having the pedals 62 suitably positioned for operation of the feet of the pilot.

15 Means is also provided for driving the shaft 38 by hand, comprising cranks 64 secured to shafts 66 in brackets 68 and carrying bevel gears 70 meshing with similar gears 72 at the front ends of flexible shafts 20 74, the rear ends of which connect with pinions 76 meshing on opposite sides of a pinion 78 carried by the shaft 38.

The sleeve 54 also carries a bevel gear 80 meshing with a similar gear 82 on a 25 shaft 84 carried by the frame of the bracket 40 and having a crank 86 for operating a rod 88 leading to a pump 90 of any suitable type for regulating the air supply as hereinafter explained. One end of this 30 pump is provided with a pipe 92 which is open at one end to the interior of the compartment 10 (see Figs. 2 and 7) and is also connected by means of a branch pipe 94 and flexible tube 95 with a float 96 which provides 35 an air inlet to said tube and pipe, a guard 98 being carried by the float to protect the inlet opening from the splash of waves. The other end of the pump 90 is connected by a pipe 100 with the reservoir 40 12, and a branch pipe 102 leads to the foul-air compartment formed by the bag 14. The several pipes are provided with the valves 104, and are furthermore connected by the cross-pipes 106 at points controlled 45 by suitable two-way valves 108,—the arrangement of pipes and valves being such that by the opening and closing of the proper valves an air flow may be caused to take place down through the pipe 94 and 50 up through the pipe 102, or in either direction through the pipes 92 and 100 at the left of the valves 108, as will be readily understood, by inspection of Fig. 7.

At the opposite sides of the vessel is 55 mounted a pair of blades 110 for operation in the rising or diving movements of the apparatus. Each blade 110 is carried by a spindle 112 journaled in a stuffingbox 114, the inner ends of the spindles being connected by a yoke 116, whereby the blades 110 may be moved in unison about a common axis. One end of the yoke 116 is extended to form a spring-like handle 118 for shifting the blades about their axes, said 60 handle being provided with a tooth 120 for

engagement with a rack segment 122 for the purpose of holding said blades in any given set position.

A pair of fin members is also provided at opposite sides of the vessel, each of said fin members comprising a comparatively stiff blade 124 carried by a sleeve 126 of suitable flexible material opening into the compartment 10, the outer or closed end of each sleeve being glove-shaped and extending for 70 a short distance free of the blade as shown in Fig. 5. The purpose of this construction is to permit the use of the pilot's arms in conjunction with said fin members as an auxiliary propelling and guiding means under certain conditions, the arms being inserted into the sleeves as indicated in Fig. 4. It will also be noted that the outer or closed ends of the sleeves are for some distance disconnected from the blades 124 for 75 80 the purpose of forming glove-shaped hand portions adapted to permit the free use of the hands of the pilot under conditions requiring it.

Beneath the compartment 10 is carried 90 a ballast section 128 which is adapted to carry a load of suitable material such as sand 130, to serve as ballast for the vessel. The section 128 is hinged at 132 adjacent the rear end of the vessel, and is releasably 95 secured at the opposite end by means of a spring latch 134, adapted to be operated from within (see Fig. 1). A screw plug 136 is provided (see Fig. 4) whereby a part of the material 130 may be allowed to flow 100 out, when desired, to lighten the load, the plug 136 being manipulated through the outer or closed end of the sleeve 126; or, the entire ballast may be discharged, in an emergency, by releasing the catch 134.

The front end of the vessel comprises a head section 140 adapted to be removably secured in place by means of a set of bolts 142, with the interior of said section in communication with the compartment 10 so as 110 to accommodate the head of the pilot. The head section is provided with observation windows 144 for viewing upward or downward, and between said windows may be mounted any suitable form of searchlight 115 146, pointing straight ahead. At opposite sides of the section 140 may also be provided a pair of membranes 148 for facilitating the transmission of sound, if desired. A trap door 150 is provided directly overhead, being hinged at 152 and held closed by a latch 154. A strong spring 156 is mounted in position to throw said door wide open when the latch 154 is operated.

In the operation of the apparatus, the 125 pilot occupies a reclining position as represented in Fig. 1, in which position he may operate any or all of the parts necessary for propelling and guiding the vessel, including the cranks 60 and 64, the hand wheel 130

34, the handle 118, the clutch lever 48 and the several valves, as well as the fin members 124. The foot power and hand power driving connections to the propeller may 5 be operated either simultaneously or alternately, and the arrangement is such that the combined operation enables the pilot to exert a more effective force than would be otherwise possible in view of his reclining 10 position. The operation of the cranks 60 at all times actuates the pump 90, and by shifting the lever 48 to the position illustrated in Figs. 1 and 2 for engaging the clutch element 42 with the gear 52, the operation 15 of said cranks 60 also drives the propeller; but if it is desired to drive the propeller by operation of the cranks 64 alone or to operate the pump by means of the cranks 60 alone the lever 48 may be thrown forward 20 into its opposite position for unclutching said gear 52. The operation of the pump is utilized for maintaining the required air-pressure within the reservoir 12, and, by proper setting of the valves 104 25 and 108, may be used for driving the foul air from the compartment 10 to the bag 14, from which any excess pressure may escape by way of the vent 16. On sinking to lower depths, beyond the range of the 30 length of tubing 95, this latter may be drawn in, the float being drawn up against the side of the vessel (see Fig. 4), and then air is admitted from the reservoir 12 into the compartment 10 as required. The 35 provision of the flexible sleeves having the blades 124 affords an effective and conveniently-operated means for exercising an auxiliary or secondary control over the movements of the vessel. The windows 144 40 enable the pilot to make observations in all directions ahead of the vessel, and the lamp 146 may be brought into use whenever needed. By manipulating the plug 136 the weight of the ballast load may be diminished, and in emergency, rendering it 45 advisable to rise to the surface, the entire ballast may be discharged by simply releasing the catch 134, whereupon the section 128 immediately swings downward on its hinges 50 132 (in the direction of the curved arrow in Fig. 4); this allows the sand to escape from the section 128, and on the vessel's rising to the surface the open position of the ballast section causes the main body of the 55 vessel to assume an upwardly tilted position, with the result that the nose or head section will be projected out of the water. Under such circumstances the pilot may take a survey in all directions at the water level, and the door 150 may be safely opened, 60 being above the water surface, allowing fresh air to be admitted, and also allowing the pilot to emerge from the vessel when circumstances permit.

It will thus be apparent that an efficient 65 and comparatively simple construction has been devised for carrying out the proposed objects of the invention, and while I have described what I now deem to represent the preferred form of embodiment of the improvements I desire to reserve the right to 70 such changes or modifications as may fairly fall within the scope of the appended claims.

Having described the invention, what I 75 claim as new and desire to secure by Letters- Patent, is:

1. A submarine apparatus comprising a vessel having a water-tight compartment, and a ballast section hinged to the rear or tail end of said vessel and releasably secured to the other end of said vessel, whereby on releasing said section the remainder of the vessel will be caused to swing into more or less upwardly-inclined position. 80

2. A one-man submarine apparatus comprising a vessel formed in sections including a main body portion and a head portion removably connected to said body portion, said sections communicating interiorly and cooperating to form a single water-tight compartment adapted to accommodate the body of the pilot in said body portion with the head of said pilot extending into said head portion of the vessel. 90

3. A submarine apparatus comprising a vessel having a water-tight compartment, and a pair of fin members arranged at the opposite sides of said vessel, each of said fin members comprising a stiff blade carried by a flexible sleeve closed at one end 100 and open at its other end into communication with said compartment. 95

4. A one-man submarine apparatus comprising a vessel having a water-tight compartment of a size adapted to accommodate the body of a pilot, and a pair of fin members arranged at the opposite sides of said vessel, each of said fin members comprising a stiff blade carried by a flexible sleeve closed at one end and open at its other end 105 into communication with the interior of said compartment, the outer ends of said sleeves being disconnected from said blades 110 to form hand portions permitting free use of the hands of the pilot. 115

In witness whereof I hereto affix my signature.

FREDERICK G. GRANTHAM,
